Claims priority, application Switzerland Jan. 12, 1970

Term of patent 14 years

Int. Cl. D23—04

U.S. Cl. D23—149

FIG. 1 is an elevational view of a vaporizer showing my new design with the vaporizer in open position, the opposite side of the vaporizer being identical;

FIG. 2 is a view showing my new design in closed position;

FIG. 3 is a top plan view thereof; and

FIG. 4 is a bottom plan view thereof.

The characteristic features of my design reside in the specific configuration of the inner tube wherein the apertures have diameters at least half the diameter of said tube.

I claim:

The ornamental design for a vaporizer, as shown and described.
